UNITED STATES PATENT OFFICE.

ELMER B. GRUSH, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BREASTING MACHINE.

Application filed February 12, 1920, Serial No. 358,094. Renewed June 7, 1923.

To all whom it may concern:

Be it known that I, ELMER B. GRUSH, a citizen of the United States, residing at Beverly, in the county of Essex and State 5 of Massachusetts, have invented certain Improvements in Heel-Breasting Machines, of which the following description, in connection with the accompanying drawings, is a specification, like reference characters on 10 the drawings indicating like parts in the several figures.

This invention relates to machines for operating upon heels and particularly to machines for shaping the breast faces of 15 French or Louis heels.

The breast faces of French and Louis heels are curved longitudinally of the heel, a portion at the base of the breast extending forwardly of the shoe along the shank. The 20 forward edges of the base portions of such heels must be made convex to correspond with the transverse curve of the shanks and be flush therewith. The breast proper of such heels, that is, the portion lying between 25 the base portion and the tread face of the heel, is frequently curved transversely of the breast and is usually concave. Frequently, too, the portion of the breast adjacent to the toplift is concaved to a greater 30 extent than the breast proper and at a less angle to the tread face of the toplift, the formation of this portion being known as scalloping.

An object of the present invention is to 35 provide a machine by which the above defined portions of the heel may be formed in the desired manner by a single operation and upon the same cutter.

A feature of the invention consists in an 40 organization comprising a rotary cutter and a shoe support arranged for relative movement to cause the cutter to traverse the heel from side to side of the heel with means for effecting, during said relative movement, 45 another relative movement in such manner as to cause the cutter to form a convex face on one portion of the breast face of the heel of the shoe and simultaneously to concave another portion of the heel breast. As 50 shown herein the cutter is ellipsoidal or egg-shaped and rotates about a fixed longitudinal axis, the second relative movement

above mentioned being effected as shown by a movement of the shoe about an axis located between the base of the heel or the 55 plane of the heelseat and the plane of its toplift and preferably in the substance of the heel itself.

A further feature of the invention consists in means for varying the position of 60 the above-mentioned axis in such a manner as to vary the extent of the portion of the heel breast which is convexed relatively to the extent of the portion which is concaved.

Another feature of the invention consists 65 in means for varying the extent of said axial movement, this adjustment causing the amount of curvature of the convexed and concaved portions of the heel breast to be varied, and particularly, causing the curvature of the convexed portion to correspond to the varying convex curves of the shanks of different shoes.

A further important feature of the invention consists in an organization by which 75 the relative predetermined position of the heel and cutter for breasting may be changed to a relative predetermined position of the heel and cutter for effecting by said cutter a scalloping of the toplift of the 80 heel, the change as shown being effected manually by a treadle. In the illustrated construction the shoe, when positioned for the scalloping operation, is turned about the before-mentioned axis to cause the scalloping 85 operation to be effected, the amount of turning movement being adjustably limited.

These and other features of the invention will appear more fully from the following detailed description when read in connection 90 with the accompanying drawings and will be pointed out in the appended claims.

In the drawings,

Fig. 1 is a side elevation of the machine;

Fig. 2 is an enlarged view of the upper 95 portion of the machine shown in Fig. 1;

Fig. 3 is a detail, in front elevation, of parts shown in Fig. 2;

Fig. 4 is a plan view showing the work support and cutter;

Fig. 5 is a sectional plan view of the line 5-5 of Fig. 2;

Fig. 6 is a sectional plan view on the line 6-6 of Fig. 2;

Fig. 7 is a perspective view of a heel with its breast formed by the machine in one adjustment thereof;

Fig. 8 is a view similar to Fig. 4 but with the parts differently adjusted;

Fig. 9 is a view similar to Fig. 6 with the parts adjusted as in Fig. 8;

Fig. 10 is a perspective view of a heel the breast of which has been formed by the machine as adjusted in Figs. 8 and 9;

Fig. 11 is a view similar to Fig. 2 showing the machine as operated to perform the scalloping operation;

Fig. 12 is a detail plan view of parts as shown in Fig. 11; and

Fig. 13 is a perspective view of a heel the breast of which has been breasted and scalloped.

Referring to Fig. 1 of the drawings, the numeral 2 indicates the column of the machine upon which is a head frame 4 provided with bearings 6, 6 for a shaft 8 having between the bearings 6 a driving pulley 10 belted to a large pulley 12 having a shaft 14 journaled in bearings located near the base of the machine and driven from any suitable source of power. In the left-hand end of the shaft 8 (Figs. 1 and 2) is a threaded socket 16 adapted to receive the threaded end 30 of a cutter member 18 having cutting edges which extend from the axis of the cutter at its end along the sides of the cutter and are arranged to trace, as the cutter rotates, an egg-shaped body. The cutter accordingly will be referred to herein as egg-shaped or ellipsoidal.

The work support includes a frame member 22 rising vertically from which are a bracket 21, carrying a plate 25 to engage the tread face of the heel, and a rest 26 to receive the tread face of the forepart of the shoe. The plate 25 is on a block 24 which is adjustably secured to a rearward projection 30 of the bracket 21 by a slot and bolt connection at 23. On the plate 25 is a stop for the rear end of the heel comprising a plate 34 having a V-shaped notch in its end to receive and center the rear part of the heel and to determine the longitudinal position of the shoe. The plate 34 is adjustable longitudinally of the shoe by means of a screw 36 threaded through a lug on the plate 34 and rotatably held in an ear 38 formed on the plate 25, a thumb head 40 being provided to enable the screw to be turned conveniently. Projecting through slots in the tread rest 26 are two stops 42, 44 which are connected together for equal and opposite adjustment by a right and left threaded screw 46 journaled in an ear 48 on the rear side of the rest 26, a thumb head 50 being provided on the screw 46 to enable the stops 42, 44 to be adjusted toward and from each other. The frame 22 is provided with hand holes 52, 54 into which the opera-

tor may insert his fingers while he uses his thumbs to press the last and shoe against the tread plate 25 and forepart rest 26 to hold the shoe in position to be operated upon. If the operator finds it more convenient he may, instead of putting his fingers through the holes 52, 54, grasp the portions of the work support which contain these holes in other ways, for instance by closing his fingers on the part at the rear of the holes.

The frame 22 is provided with a cylindrical hub portion 55 which is embraced by a two-part bearing 56, 58 on the end of a link 60, the opposite end of which is pinned to a vertical shaft 62 which forms a pivot for it. The two parts 56, 58 of the bearing are held together in bearing engagement with the hub of the frame 22 by screws 64. The pivot shaft 62 of the link is fixed as to horizontal movement but can move vertically as the shoe support is raised to effect passage of the work across the cutter 18. For this purpose the shaft 62 is arranged to turn in a bearing formed in a bracket 68 (Fig. 6) formed on a slide 69, to be described hereinafter, and is also movable longitudinally therein, the shaft 62 being sufficiently long to permit the required vertical movement of the shoe past the cutter (Fig. 11). On the frame member 22 just beneath the cylindrical portion 55, engaged by the bearing 56, 58, is a portion 70 formed with a segmental T-guideway which is engaged by a T-head 72 fixed to the upper end of a vertical hollow shaft 74. The shaft 74 is journaled in bearings 76, 78 and arranged also for longitudinal movement therein. The bearings 76, 78 are connected by a rigid web 80 and are provided with arms 82, 84. The arm 82 of the upper bearing 76 is pivoted by a screw 86 to the slide 69 and the lower arm 84 is pivoted to an ear 88 formed on a depending portion 90 of the slide 69. The pivot of the arm 84 is formed by the upper end of a shaft 92 which passes through the arm 84 and is threaded into the ear 88, the shaft being in vertical alignment with the pivot 86. It will be seen that the bearings 76, 78 connected by the web 80 are movable about a vertical axis passing through the pivots 86, 92. The curvature of the T-head 72 and guideway 70 is struck from the pivot 86 as a center. The position of the bearings about this axis is adjustably determined at the will of the operator by a spring pin 94 mounted in an extension 96 of the arm 82 beyond its pivot 86, the spring pin 94 being arranged to engage any one of a series of holes 89 formed in a projection 100 of the slide 69. By lifting the spring pin 94 by its knob 95 the operator may swing the extension 96 in either direction and cause movement of the bearings 76, 78 in the opposite direction about the vertical axis 86 and may place the axis

of the shaft 74 either in alinement with the axis of the hub 55 of the frame 22 or at either side of that axis for a purpose to be explained hereinafter, it being assumed for the present that the hub 55 and shaft 74 are in alinement.

A lower portion 154 of the hollow shaft 74 is of reduced size and encloses a rod 155 which is connected at its lower end by a ball and socket joint to a rod 104 which is connected to a treadle 106 pivoted at 108, so that depression of the treadle 106 will effect upward movement of the rod 155 and, by reason of an enlargement 157 of the rod 155 which engages the lower end of the portion 154, will effect upward movement of the shaft 74, 154, and with it the upward movement of the shoe supporting frame 22 to cause the cutter to traverse the shoe from side to side of the heel. The shoe, however, is free to turn about the axis of the shaft 74 and its movement about that axis is controlled by mechanism now to be described.

On the web 80 between the bearings 76, 78 is mounted an adjustable cam 110 (Fig. 3) which may comprise one or more leaf springs, the ends of which are held in a recess 112 formed in the inner face of a block 114 secured at 116 to the web 80. The cam 110 is engaged centrally of its inner face by a screw 120 threaded through the block 114 and provided with a capstan head 121. By means of the screw 120 the springs of the cam 110 are forced to a greater or less extent through an open side of the recess 112, the springs or cam 110 then being in the path of a roll 122 mounted on a collar 124 (Fig. 2) fixed by a pin 125 to a rod 127 inside the hollow shaft 74. The lower end of the rod 127 rests on the upper end of the rod 155 so that when the treadle 106 is operated the shaft 74, rods 155 and 127, and collar 124 with its roll 122, are raised together as a unit, the pin 125 engaging the upper end of the slot 129 in the hollow shaft 74, the pin lying in a slot 129 in the hollow shaft 74 to permit movement of the shaft relatively to the pin, collar 124 and rod 127, for a purpose which will later appear. Surrounding the shaft 74 is a combined compression and torsion spring 126 which is secured at one end to the collar 124 and at the other end to a collar 128 loose on the shaft 74 and having teeth on its upper face to engage corresponding teeth formed on the bearing 76. The torsional tension on the spring 126 tends to turn the shaft 74 and the shoe support to hold the roll 122 against a face 130 of the block 114 and cam 110. The tension of the spring 126 may be varied by turning the collar 128 which is provided with capstan holes for this purpose.

When the treadle 106 is depressed to move the shaft 74 longitudinally its movement will be opposed by the spring 126 which acts as

a return spring for the shoe support, and during its longitudinal vertical movement the roll 122 will at first engage the face 130 of the block 114 (Fig. 3) as explained. When the shoe has reached a point such that the heel is about to be engaged by the cutter the roll 122 will reach the cam 110. As the vertical movement of the shaft 74 continues the roll 122 will be moved to the left by engagement with the cam 110 and hence the shaft 74 will be turned at first in a clockwise direction against the spring 126, and then will be turned by the spring in an opposite or counter-clockwise direction as the roll 122 passes the top of the cam 110, carrying with it, of course, the shoe support and shoe. Referring to Fig. 4, it will be seen that the cam 110 causes a rocking movement of the shoe about the center of the hub 55 which coincides, in the position shown, with the axis of the shaft 74, and that, therefore, as the shoe passes the cutter said rocking movement will cause the portion of the breast adjacent to the toplift to be concaved, the depth of the concavity diminishing from the tread face toward the axis 55. At the same time the base portion of the heel which extends along the shank will be moved first away from the cutter and then toward it, so that in conjunction with the movement of the heel about the axis 55 to cause the breast to be concaved, there will be corresponding movement of the base portion of the heel first away from and then toward the cutter to cause the base portion of the heel to be formed with a convex curvature corresponding to the curve of the shank. The shape of the heel breast resulting from the operation of the machine as described is shown in Fig. 7. The portion of the breast at *a* is convex, the convexity diminishing from the shank line *d-d*, where it coincides with the curvature of the shank, toward the line *b-b*, and the portion *c* of the breast is concave, the concavity increasing from the line *b-b* toward the tread face of the heel. At the line *b-b* the breast is substantially straight transversely of the heel.

The movement of the shoe and the resulting operations of the cutter upon the shoe may be varied and modified to adapt the machine for different conditions of work by changing the location of the axis of the shaft 74 with relation to the axis of the hub 55 on which the shoe support and frame 22 turn. This is effected, in the construction described, by releasing the spring pin 94 and turning the extension 96 on the axis 86 to vary the position of the shaft 74 eccentrically with the axis of the hub 55. From Fig. 6 it will be seen that the T-head guide 70 formed on the hub 55 and the T-head 72 on the shaft 74 are curved concentrically with the pivot 86. Hence, positioning of the axis of the shaft 74 eccentrically with the axis of the hub 55

will cause no displacement of the hub 55 and the work support. When, however, the work support is raised after this eccentric adjustment has been made, rocking of the shaft 74 by the cam 110 will effect movement of the shoe support about a differently located center which center, by the adjustment described, may assume various positions between the plane of the heel seat and the plane of the toplift. This results in varying the area of the heel which is convexed relatively to the area concaved. Thus, with the pin 94 in the last hole at the right (Fig. 4) a greater portion of the breast surface would be concaved and less convexed, while with the pin 94 in the opposite extreme position, as shown in Figs. 8 and 9, the surface of the breast would be substantially all convexed except the breast edge of the toplift which would be substantially straight, as shown in Fig. 10. In this adjustment (Fig. 8) the center of the hub 55 remains as before but the center of turning movement 74 has been shifted until it lies substantially in the plane of the tread face of the heel. Turning of the heel about the center 74 as it traverses the cutter will, therefore, cause substantially all parts of the breast of the heel to be convex and the amount of convexity at the shank can be varied of course by adjusting the cam 110 to vary the amount of turning movement.

In a machine organized as shown herein, the operator may now, while holding the shoe on the work support in the same position, perform the operation of forming in the toplift portion of the heel breast a more pronounced concavity or scallop. The work support, as described, is mounted on the slide 69. This slide extends transversely of the machine frame in a direction parallel with the shaft 8 and roller bearings 140 are suitably arranged in the frame to permit free movement of the slide 69 in a horizontal direction. In the rear face of the depending portion 90 of the slide 69 a T-way 142 (Fig. 5) is formed in which a T-block 144 is arranged for vertical sliding movement. On the T-block 144 is a cam face 146 (Figs. 2 and 11) and the T-block 144 is connected by a rod 148 to one end of a link 150, the other end of which is pivoted on the shaft 92. A member 152 is arranged to slide vertically on the shaft 92 and is formed to embrace the link 150 so that vertical movement of the member 152 compels vertical movement of the link 150 and hence of the T-block 144 and cam face 146. The reduced lower end 154 of the shaft 74 passes freely through the member 152 and the shoulder formed by the reduction rests in the upper face of the member 152. The member 152 is connected by a rod 156 with a treadle 158 arranged beside the treadle 106 and pivoted on the same axis 108. When the treadle 158

is depressed the member 152 is lifted, carrying with it the shaft 74 and, of course, the work support, and sliding on the shaft 92. At the same time movement is imparted through the rod 148 to the cam face 146 causing it to engage a roller 160 having a fixed axis on the machine frame. When the cam face reaches the roll 160 the slide 69 is moved outwardly of the machine frame against a tension spring 162 connected between the frame and the depending portion 90 of the slide. This movement, of course, carries the shoe away from the cutter in the direction of the cutter axis. When sufficient vertical movement has been imparted to the shoe to bring the center of the heel breast or the longitudinal median plane of the shoe into coincidence with the cutter axis, the member 152 engages an adjustable collar 164 on the shaft 92 which limits further upward movement of the shoe. In order to cause the shoe heel to engage the cutter it is necessary to turn the shoe and its support on the shaft 74, and means is provided adjustably to limit this turning movement so that the depth of the scalloping cut may be controlled. For this purpose the collar 164 is provided with a projection 166 (Fig. 5) which is in position to engage a stop screw 168 threaded through the web 80 and is provided with a thumb head 170.

During vertical movement of the shoe for the scalloping operation it is desirable that the cam roll 122 remain at rest to give free control of turning movement, for effecting the scalloping operation, to the operator and to avoid any possible interference with that movement by engagement of the cam roll 122 with its cam 110. In the construction shown the roll will remain at rest when the shoe is raised by the right hand treadle 158. This is because the lifting force is applied to the shaft 74 through the member 152 and the rod 155 in the lower part 154 of the shaft 74 remains at rest as does also the rod 127 and the block 124 held to it by the pin 125, vertical movement of the hollow shaft 74 being permitted by the slot 129. The spring 126 tends to hold the block 124 down during elevation of the shaft 74 for the scalloping operation. After the shoe has been elevated by operation of the treadle 158, as shown in Fig. 11, the shoe may be turned clockwise to bring the heel into engagement with the cutter, as shown in Fig. 12, the depth of the cut being limited by engagement of the lug 166 with the screw 170. The adjustment of the screw is preferably such that the scallop extends from corner to corner of the heel breast, as illustrated in Fig. 13, which shows a heel after the breasting and scalloping operations have been performed. A compression spring 172 is provided on the shaft 74 between the member 130

152 and the arm 84 to insure return movement of the cam 146 when the treadle 158 is released after the scalloping operation. The amount of longitudinal movement of 5 the slide 69 effected by vertical movement of the shoe support may be varied by means shown in Figs. 2 and 11 where it will be seen that the inner portion of the cam face 146 of the T-block 144 is formed on the upper 10 ends of plates 145 which are slotted and are held in place on the T-block 144 by a screw 147 passing freely through the slots in the plates 145 and threaded into the block 144. By loosening the screw 147 one or 15 more of the plates 145 may be moved downwardly out of operative relation to the roll 160 and hence the amount of movement of the shoe support lengthwise of the cutter shaft effected by upward movement of the 20 block 144 may be varied with the result that the portion of the tread face of the heel adjacent to the toplift in which the scallop is made will be located opposite different portions of the cutter. Hence a portion of 25 the cutter may be selected which is of the shape and diameter to produce the desired form of scallop upon the heel.

Having thus described my invention, what I claim as new and desire to secure by 30 Letters Patent of the United States is:

1. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, and means acting during said relative movement for causing relative movement of the heel and cutter about an axis to cause the heel breast to be formed with one portion concaved and another portion convexed.

2. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, and means acting during said relative movement for causing relative movement of the heel and cutter about an axis located between the plane of the heelseat and the plane of the toplift to cause the heel breast to be formed with one portion concaved and another portion convexed.

3. A machine of the class described having, in combination, a shoe support for locating a shoe and its attached heel in predetermined position, a rotary cutter, and means for effecting relative movement between the support and cutter to cause relative traverse of the shoe heel and cutter, said support

being mounted for movement to turn the shoe about an axis to cause one portion of the heel breast to be formed with a convexed surface and another portion to be formed with a concaved surface.

4. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, and means acting during said relative movement to cause one portion of the heel breast to be formed with a convexed surface and another portion to be formed with a concaved surface.

5. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, and means acting during said relative movement for causing relative movement of the heel and cutter about an axis located between the plane of the heelseat and the plane of the toplift to cause the base portion to be formed with a convexed surface and the portion next to the toplift to be formed with a concaved surface.

6. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, and means acting during said relative movement for causing relative movement of the heel and cutter about an axis located between the plane of the heelseat and the plane of the toplift to cause the base portion to be formed with a convexed surface, the portion next to the toplift to be formed with a concaved surface, and the portion between said portions to be formed substantially straight transversely of the heel.

7. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, and means acting during said relative movement for causing relative movement of the heel and cutter about an axis located adjacent to the seat face of the heel and at a substantial distance longitudinally of the heel from the forward edge of the base portion to cause

one portion of the heel breast to be concaved and another portion convexed.

8. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, means acting during said relative movement for causing relative movement of the heel and cutter about an axis located between the plane of the heelseat and the plane of the toplift to cause the heel breast to be formed with one portion concaved and another portion convexed, and means for locating said axis at various points in the direction of the height of the heel.

9. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, means acting during said relative movement for causing relative movement of the heel and cutter about an axis located between the plane of the heelseat and the plane of the toplift to cause the heel breast to be formed with one portion concaved and another portion convexed, and means for locating said axis at various points in the direction of the height of the heel, said points being in the substance of the heel and substantially uniformly distant from the breast face of the heel.

10. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, means acting during said relative movement for causing relative movement of the heel and cutter about an axis located between the plane of the heelseat and the plane of the toplift to cause the heel breast to be formed with one portion concaved and another portion convexed, and means for varying the relative turning movement about said axis to cause the degree of convexity of the convexed portion to correspond to the curvature of the shoe shank.

11. A machine of the class described having, in combination, a shoe support for locating a shoe and its attached heel in predetermined position, a rotary cutter, means for effecting relative movement between the support and cutter to cause relative traverse of the shoe heel and cutter in a direction

from side to side of the heel, means acting during said relative movement for causing relative movement of the heel and cutter about an axis located between the plane of the heelseat and the plane of the toplift to cause the base portion to be formed with a convexed surface and the portion next to the toplift to be formed with a concaved surface, and means for varying the location of said axis to cause the area of the concaved portion to be varied.

12. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, means acting during said relative movement for causing relative movement of the heel and cutter about an axis located between the plane of the heelseat and the plane of the toplift to cause the base portion to be formed with a convexed surface and the portion next to the toplift to be formed with a concaved surface, and means for varying the location of said axis in the direction of the height of the heel to cause the area of the concaved portion to be varied.

13. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, and means acting during said relative movement for causing relative movement of the heel and cutter about an axis parallel to the shoe bottom and so located that relative movement of the shoe and cutter about said axis will cause the base portion of the heel to be convexed to correspond to the curve of the shank and the portion next to the toplift to be concaved.

14. A machine of the class described having, in combination, a shoe support for locating a shoe and its attached heel in predetermined position, a rotary cutter, means for effecting relative movement between the support and cutter to cause relative traverse of the shoe heel and cutter in a direction from side to side of the heel, means acting during said relative movement for causing relative movement of the heel and cutter about an axis parallel to the shoe bottom and so located that relative movement of the shoe and cutter about said axis will cause the base portion of the heel to be convexed to correspond to the curve of the shank and the portion next to the toplift to be concaved, means for varying the location of said axis to cause more or less of the heel breast to be concaved,

and means for varying the amount of rotative movement about said axis to cause the curvature of the base portion of the heel to correspond to the curves of differently curved 5 shoe shanks.

15. A machine of the class described having, in combination, a rotary cutter, a shoe support, means for effecting relative rectilinear movement between the cutter and support to cause the cutter to traverse the heel breast from side to side of the heel, and means operating during said relative movement to cause the shoe to turn on an axis parallel to the heel breast and to cause the 10 breast to be transversely curved.

16. A machine of the class described, having, in combination, a rotary cutter, a shoe support, means for effecting relative rectilinear movement between the cutter and support to cause the cutter to traverse the heel breast from side to side of the heel, and means operating during said relative movement to cause a relative rotative movement of the cutter and shoe in such a manner that 20 the breast of the heel is formed with a transverse curvature decreasing from the base of the heel toward its tread face.

17. A machine of the class described having, in combination, a rotary cutter having a fixed axis of rotation, shoe supporting means 30 movable transversely of the cutter axis to cause the shoe to traverse the cutter from side to side of the heel, and means for causing the shoe to turn about an axis adjacent to the heel breast.

18. In a machine of the class described, the combination of a rotary cutter, a shoe support to locate the shoe in predetermined position, means for moving the shoe perpendicular to the cutter axis, and means for effecting oscillation of the shoe support during such movement about an axis parallel with its direction of movement across the cutter.

19. In a machine of the class described, the combination of a rotary cutter, a shoe support to locate the shoe in predetermined position, means for moving the shoe perpendicular to the cutter axis, and means for effecting oscillation of the shoe support during such movement about an axis parallel with the plane of the tread face of the heel.

20. In a machine of the class described, the combination of a rotary cutter, a shoe support to locate the shoe in predetermined position, means for moving the shoe perpendicular to the cutter axis, and means for effecting oscillation of the shoe support during such movement about an axis parallel with its direction of movement across the cutter and located between the plane of the seat face and the plane of the tread face of the heel.

21. In a machine of the class described, the combination of a rotary cutter, a shoe support movable relatively to the cutter to cause

the shoe to traverse the cutter from side to side of the heel, a link arranged substantially perpendicular to the tread face of the heel of a shoe on the support having one end pivoted to the shoe support and about which the 70 shoe support can turn and having the other end pivoted at a point fixed relatively to the shoe support and at a substantial distance from the heel, and means for causing the shoe support to turn on its pivot to the link during its movement across the cutter about a center which may be varied relatively to the link in the direction of the height of the heel.

22. A machine of the class described having, in combination, means for locating a shoe and its attached heel in predetermined position, a rotary cutter having an axis at an obtuse angle to the tread face of the heel of the shoe so positioned, means for moving the shoe in a direction perpendicular to the cutter axis to cause the cutter to traverse the heel breast from side to side, and means for oscillating the shoe back and forth during its passage across the cutter to cause the breast face to be transversely curved.

23. In a machine of the class described, the combination of shoe positioning means for locating a shoe and its attached heel, a substantially ellipsoidal rotary cutter mounted for rotation on its major axis, said axis being disposed at a substantially obtuse angle to the plane of the tread face of the shoe heel and parallel to the longitudinal median pane of the shoe, and means for effecting relative rectilinear movement 90 between the shoe support and cutter to cause the cutter to breast the heel.

24. In a machine of the class described, the combination of shoe positioning means for locating a shoe and its attached heel with its longitudinal median plane substantially horizontal, a substantially ellipsoidal rotary cutter mounted for rotation on a horizontal axis disposed at an obtuse angle 105 to the plane of the tread face of the heel, and means for effecting relative rectilinear movement between the shoe support and cutter to cause the cutter to breast the heel.

25. In a machine of the class described, the combination of shoe positioning means for locating a shoe and its attached heel, a rotary cutter mounted for rotation on an axis disposed at a substantial angle to the plane of the tread face of the shoe and parallel to its longitudinal median plane, means for effecting relative rectilinear movement between the shoe support and cutter to cause the cutter to breast the heel, and means acting in conjunction with said relative movement to effect relative movement of the shoe and cutter about an axis parallel to the breast face of the heel to cause the cutter to form a transversely curved face on the heel breast.

26. In a machine of the class described,

- the combination of means for convexing the shank portion of a heel and for concaving the remaining portion of the breast of the heel, and a heel support between which and said means there is provision for relative rectilinear movement and for movement about an axis adjacent to the heel-breast to cause said means so to operate on the heel.
27. In a machine of the class described, 10 the combination of a rotary cutter and shoe supporting means relatively movable to cause the shoe to traverse the cutter from side to side of the heel, and means to cause a relative turning movement of the shoe and cutter about an axis adjacent to the heel breast to cause a portion of the heel to be formed with a convexed surface and a portion of the heel to be formed with a concaved surface.
28. In a machine for operating upon the 20 heels of boots and shoes, the combination of a rotary cutter, a shaft, a heel carrier on the shaft, means for effecting longitudinal movement of the shaft to cause the breast of the heel to traverse the cutter, and cam operated connections acting during said movement of the shaft to effect turning movement of the shaft for causing the breast face of the heel to be transversely curved.
29. In a machine of the class described, 30 the combination of a rotary cutter, shoe supporting means movable to cause the shoe to traverse the cutter from side to side of the heel, and means to cause the shoe to turn about an axis adjacent to the heel breast to cause a portion of the heel on one side of the axis to be formed with a convexed surface and a portion of the heel on the other side of the axis to be formed with a concaved surface.
30. In a machine of the class described, 40 the combination of a rotary cutter, shoe supporting means movable to cause the shoe to traverse the cutter from side to side of the heel, means to cause the shoe to turn about an axis adjacent to the heel breast to cause a portion of the heel on one side of the axis to be formed with a convexed surface and a portion of the heel on the other side of the axis to be formed with a concaved surface, and means constructed and arranged to enable the location of said axis to be varied in the direction of the height of the heel.
31. In a machine of the class described, 50 the combination of a rotary cutter, shoe supporting means movable to cause the shoe to traverse the cutter from side to side of the heel, means to cause the shoe to turn about an axis adjacent to the heel breast to cause a portion of the heel on one side of the axis to be formed with a convexed surface and a portion of the heel on the other side of the axis to be formed with a concaved surface, and means for varying the location of said

axis to vary the area of the surface which is convexed relatively to the area of the surface which is concaved.

32. In a machine of the class described, the combination of a rotary cutter, a shoe support to locate the shoe in predetermined position, manual means for moving the shoe in a right line perpendicularly to the cutter axis, and means acting without attention on the part of the operator for effecting oscillation of the shoe support during such movement about an axis parallel to the direction of the manually effected movement of the shoe support.

33. In a machine of the class described, 80 the combination of a rotary cutter having a curved cutting face, a shoe support to locate the shoe in predetermined position, means for moving the shoe support perpendicularly to the cutter axis to carry the shoe 85 heel across the cutter and to cause the cutter to form the heel with a longitudinal curvature, and means for moving the portion of the breast face adjacent to the tread face toward and from the cutter about a center 90 located adjacent to the base of the heel.

34. In a machine of the class described, the combination of a rotary cutter having a curved cutting face, a shoe support, a link arranged to maintain the support in predetermined relation to the end of the cutter and having one end pivoted to the shoe support so that the shoe support can turn, a segmental member on the support having a 100 slideway beneath its turning point, a shaft 105 having fixed thereto a slide engaging said slideway, means for moving the shaft longitudinally to carry the support across the cutter, means for causing the shaft to turn during its longitudinal movement, and means for positioning the shaft concentric or eccentric to the turning point of the shoe support.

35. A machine of the class described having, in combination, a shoe support for locating the shoe and its attached heel in predetermined position, a rotary cutter having cutting edges extending from its center of rotation along its sides and having a contour corresponding to the shape of the heel breast to be formed, means for effecting relative movement between the shoe support and the cutter in a direction perpendicular to the cutter axis to cause relative traverse of the heel and cutter from side to side of the heel, means for causing, during said relative movement, relative movement of the shoe and cutter about an axis located in the heel adjacent to its breast, and means for varying the location of said axis in the direction of the height of the heel.

36. In a machine of the class described, the combination of means for convexing the shank portion of a heel and for concaving the portion of the breast of the heel adjacent to its tread face, and a heel support between 130

which and said means there is provision for relative rectilinear movement transversely of the shoe and for movement about an axis located between the planes of the seat and 5 tread faces of the heel to cause said means so to operate on the heel.

37. In a machine for operating upon the 10 heels of boots and shoes, the combination of a rotary cutter, a heel carrier, and means for effecting movement of the carrier to cause the heel to be breasted and then to cause the portion of the breast adjacent to the tread face of the heel to be concaved.

38. In a machine of the class described, 15 the combination of means for locating a shoe and its attached heel in predetermined position, a rotary cutter having an axis at an obtuse angle to the tread face of the heel of the shoe so positioned, means for moving the 20 shoe locating means in a direction perpendicular to the cutter axis, means for arresting movement of the shoe locating means when the center of the heel breast is in line with the axis of the cutter, and means enabling 25 the shoe locating means to be moved in the longitudinal median plane of the shoe to cause the cutter to form a scallop in the breast face of the heel.

39. In a machine of the class described, 30 the combination of shoe positioning means for locating a shoe and its attached heel with its longitudinal median plane substantially horizontal, a rotary cutter mounted for rotation on a horizontal axis disposed at a substantial angle to the plane of the tread face of the shoe, means for effecting rectilinear movement between the shoe positioning means and the cutter to cause the cutter to breast the heel, separate means for effecting 35 rectilinear movement between the shoe positioning means and cutter to a less extent and for effecting separation of the shoe and cutter, means enabling the shoe positioning 40 means to be turned to cause the cutter to treat only the portion of the breast face adjacent to the top lift, and means to limit the 45 turning movement.

40. A machine of the class described having, in combination, means for locating a 50 shoe and its attached heel in a predetermined position, a rotary cutter mounted on an axis at an obtuse angle to the tread face of the heel and parallel to the longitudinal median plane of the shoe, means for relatively moving the shoe and cutter in a direction perpendicular to the axis of the cutter to breast the heel, and means for relatively separating the shoe and cutter in the direction of the cutter axis, the shoe and cutter being then 55 relatively movable about an axis parallel to the breast face of the heel to cause a further conformation to the breast face adjacent to the top lift to be effected.

41. A machine of the class described having, in combination, a rotary cutter having

a fixed axis of rotation, shoe supporting means movable transversely of the cutter axis to cause the shoe to traverse the cutter from side to side of the heel, means for maintaining the shoe support at a fixed distance from the cutter, a shaft parallel to the direction of movement of the support transversely of the cutter on which the shoe support is mounted for turning movement, and means for varying the position of 70 said shaft relatively to the shoe support to vary the position of the axis of turning movement of the support relatively to the cutter.

42. In a machine of the class described, 80 the combination of shoe positioning means for locating a shoe and its attached heel with its longitudinal median plane substantially horizontal, a rotary cutter mounted for rotation on a horizontal axis disposed at a substantial angle to the plane of the tread face of the shoe, means for effecting relative rectilinear movement between the shoe positioning means and cutter to cause the cutter to breast the heel, 85 means acting in conjunction with said relative movement to effect relative movement of the shoe and cutter about a vertical axis to cause the cutter to form a transversely curved face on the heel breast, separate means for effecting relative rectilinear movement between the shoe positioning means and cutter to bring the longitudinal median plane of the heel into coincidence with the axis of the cutter, and means acting simultaneously with said second relative movement to effect a relative movement of separation between the heel and cutter in the direction of the cutter axis, the shoe positioning means and cutter being then relatively movable as before about a vertical axis to cause the cutter to scallop the heel. 90

43. A machine of the class described having, in combination, a rotary cutter, a shoe support, means for effecting relative movement between the cutter and support to cause the cutter to traverse the heel breast from side to side of the heel, a cam operating during said relative movement to effect another relative movement between the shoe and cutter to cause the breast to be transversely curved, and means for varying the curvature of the cam. 105

44. A machine of the class described having, in combination, a rotary cutter, a shoe support, means for effecting relative movement between the cutter and support to cause the cutter to traverse the heel breast from side to side of the heel, a cam operating during said relative movement to cause a relative movement of the cutter and shoe in such a manner that the breast of the heel is formed with a transverse curvature decreasing from the base of the heel toward 115 its tread face, and means for varying the 120

curvature of the cam to increase or diminish said transverse curvature.

45. A machine of the class described having, in combination, a rotary cutter having 5 a fixed axis of rotation, a shoe support mounted for turning movement on an axis adjacent to the heel breast and movable transversely of the cutter axis to cause the shoe to traverse the cutter from side to side 10 of the heel, and a cam acting during said transverse movement to cause turing movement of the support about its axis.

46. A machine of the class described having, in combination, a rotary cutter having 15 a fixed axis of rotation, shoe supporting means movable in a right line perpendicular to the cutter axis to cause the shoe to traverse the cutter from side to side of the heel, and means for causing the shoe to move 20 about a line parallel to the direction of said perpendicular movement.

47. A machine of the class described having, in combination, a rotary cutter having 25 a fixed axis of rotation, shoe supporting means movable transversely of the cutter axis to cause the shoe to traverse the cutter from side to side of the heel, means for causing the shoe to turn on an axis adjacent to the heel breast, and means which 30 may be adjusted to greater or less eccentricity to said axis to vary the position of the axis about which the shoe turns.

48. In a machine of the class described, 35 the combination of a rotary cutter, a shoe support to locate the shoe in predetermined position, means for moving the shoe perpendicularly to the cutter axis, means for effecting oscillation of the shoe support during such movement about an axis parallel with its direction of movement across the cutter, and adjustable means for varying the extent of said oscillation.

49. In a machine of the class described, 45 the combination of a rotary cutter, a shoe support having a supporting post which is movable longitudinally relatively to the cutter to cause the shoe to traverse the cutter from side to side of the heel, a link arranged substantially perpendicular to the 50 tread face of the heel of a shoe on the support having one end pivoted to the shoe support at a point normally concentric with the post and about which the shoe support can turn and having the other end pivoted to the shoe support at a substantial distance 55 from the heel, means for causing the shoe support to turn on its pivot to the link during its movement across the cutter, and means constructed and arranged to enable the post 60 to be positioned eccentrically of the adjacent pivot of the link for causing movement of the shoe support about a differently located center.

50. A machine of the class described having, in combination, means for locating a 65

shoe and its attached heel in a predetermined position, a rotary cutter mounted on an axis at an obtuse angle to the tread face of the heel and parallel to the longitudinal median plane of the shoe, means for relatively moving the shoe and cutter in a direction perpendicular to the axis of the cutter to breast the heel, means for relatively separating the shoe and cutter in the direction of the cutter axis, and means for relatively moving the shoe and cutter about an axis parallel to the breast face of the heel to cause the breast face adjacent to the top-lift to be scalloped.

51. In a machine of the class described, 80 the combination of shoe positioning means for locating a shoe and its attached heel with its longitudinal median plane substantially horizontal, a rotary cutter mounted for rotation on a horizontal axis disposed at a substantial angle to the plane of the tread face of the shoe, means for effecting relative rectilinear movement between the shoe positioning means and cutter to cause the cutter to breast the heel, separate means for effecting relative rectilinear movement between the shoe positioning means and cutter to a less extent and for effecting relative separation of the shoe and cutter, means 85 enabling the shoe positioning means to be turned to cause the cutter to treat only the portion of the breast face adjacent to the top-lift, and means to limit the turning movement.

52. In a machine of the class described, 90 the combination of shoe positioning means for locating a shoe and its attached heel with its longitudinal median plane substantially horizontal, a rotary cutter mounted for rotation on a horizontal axis disposed at a substantial angle to the plane of the tread face of the shoe, means for effecting relative rectilinear movement between the shoe positioning means and cutter to cause the cutter to breast the heel, means acting 95 in conjunction with said relative movement to effect relative movement of the shoe and cutter about a vertical axis to cause the cutter to form a transversely curved face on the heel breast, separate means for effecting relative rectilinear movement between the shoe positioning means and cutter to bring the longitudinal median plane of the heel 100 into coincidence with the axis of the cutter, and means acting simultaneously with said second relative movement to effect a relative movement of separation between the heel and cutter in the direction of the cutter axis, the shoe positioning means and cutter being 105 then relatively movable as before about a vertical axis to cause the cutter to scallop the heel.

53. In a machine of the class described, 110 the combination of means for locating a shoe and its attached heel in predetermined 115

- position, a rotary cutter having a fixed axis of rotation, means for moving the shoe in a direction perpendicular to the cutter axis, means for arresting movement of the shoe 55
- locating means when the center of the heel breast is in line with the axis of the cutter, and means enabling the shoe locating means to be turned in the longitudinal median plane of the shoe to cause the cutter to form 10 a scallop in the breast face of the heel. 70
54. In a machine of the class described, the combination of shoe positioning means for locating a shoe and its attached heel with its longitudinal median plane substantially horizontal, a rotary cutter mounted for rotation on a horizontal axis, means for effecting relative rectilinear movement between the shoe positioning means and cutter to bring the longitudinal median plane 15 of the heel into coincidence with the axis of the cutter, and means acting simultaneously with said relative movement to effect separation between the heel and the cutter, the shoe positioning means and the cutter being relatively movable about a vertical axis to cause the cutter to scallop the heel, and means for adjustably varying said relative movement of separation of the heel and cutter to vary the scalloping action of the cutter. 75
58. A machine of the class described having, in combination, a shoe support for locating a shoe and its attached heel in predetermined position, a rotary cutter, means for effecting relative rectilinear movement between the support and cutter to cause relative traverse of the shoe heel and cutter in a direction from side to side of the heel, said support being movable about an axis parallel to the shoe bottom and so located that relative movement of the heel and cutter about said axis will cause the portion of the heel next to the toplift to be concaved, and means for varying the relative position of the cutter and support in the direction of the height of the heel. 80
55. In a machine of the class described, the combination of means for locating a shoe and its attached heel in predetermined position, a rotary cutter having an extended cutting face, means for moving the shoe locating means in a direction perpendicular to the cutter axis, means for arresting the 20 movement of the locating means when the center of the heel breast is in line with the axis of the cutter, adjustable means acting in conjunction with said movement of the shoe locating means perpendicularly to the cutter axis to locate the treated portion of the heel breast opposite different portions of the cutting face of the cutter, and means enabling the shoe locating means to be moved in the horizontal median plane of the shoe to cause the cutter to form a scallop 25 on the breast face of the heel. 90
59. In a machine of the class described, the combination of shoe positioning means, a rotary cutter, and means for relatively moving the cutter and positioning means to cause the base portion of the heel to be convexed and the breast of the heel to be formed with one part convexed and another part concaved. 95
60. In a machine of the class described, the combination of shoe positioning means, a rotary cutter, and means for relatively moving the cutter and shoe positioning means to cause an intermediate portion of the heel breast to be transversely straight and one end portion to be concaved and the other convexed, the curvatures increasing in degree from said intermediate portion. 100
61. In a machine of the class described, the combination of a rotary cutter, and means for positioning a shoe arranged for rectilinear movement substantially perpendicular to the cutter axis to locate the heightwise center line of the heel breast and the cutter axis in the same plane, said positioning means and the cutter being arranged for relative movement about an axis perpendicular to the cutter axis to cause the heel breast to engage the cutter. 105
62. In a machine of the class described, the combination of a rotary cutter having a permanently fixed axis of rotation, and means for positioning a shoe with the heightwise center line of the heel breast and the cutter axis in the same plane, said positioning means being arranged for move- 110
56. In a machine of the class described, the combination of shoe positioning means for locating a shoe and its attached heel with its longitudinal median plane substantially horizontal, means for effecting rectilinear movement between the shoe positioning means and cutter to locate the cutter opposite the portion of the heel breast adjacent to the toplift, means enabling the shoe positioning means to be turned to cause the cutter to treat only the portion of the breast face adjacent to the toplift, and means to limit the turning movement. 115
57. In a machine of the class described, the combination of shoe positioning means for locating a shoe and its attached heel with its longitudinal median plane substantially horizontal, a rotary cutter mounted for rotation on a horizontal axis, means 120
- 65

ment about an axis perpendicular to the cutter axis to cause the heel breast to engage the cutter.

63. In a machine of the class described, the combination of an egg-shaped cutter mounted for rotation on its longitudinal axis, means for positioning a heel, said positioning means being movable substantially at right angles to the cutter axis to cause the cutter axis to lie in the longitudinal median plane of the heel, and means permitting relative movement of the positioning means and the cutter about an axis perpendicular to the cutter axis to cause the portion of the heel breast adjacent to its tread face to engage the cutter.

64. In a machine of the class described, the combination of an egg-shaped cutter mounted for rotation on its longitudinal axis, and means for positioning a heel movable transversely of the cutter axis to cause the cutter axis to lie in the longitudinal median plane of the heel, said positioning means being then movable about an axis perpendicular to the cutter axis to cause the portion of the heel breast adjacent to its tread face to engage the cutter.

65. In a machine of the class described, the combination of means for positioning the tread face of a shoe, handles on the positioning means extending longitudinally beyond the shoe and arranged to be grasped by the operator's fingers while his thumbs engage the shoe, means for operating on the shoe bottom, and means for relatively moving the positioning means and the operating means.

66. In a machine of the class described, the combination of positioning means against which a shoe is held by the hands of the operator, and extensions on the positioning means provided with finger holes located to receive the fingers of the operator's hands while his thumbs press opposite ends of the shoe against the positioning means.

67. In a machine of the class described, the combination of means for engaging the forepart of a shoe, means for locating the heel of the shoe, and a handle extending beyond the rear part of the shoe in position to be grasped by the fingers of the operator's hand while his thumb presses the rear part of the shoe against the heel locating means.

68. In a machine of the class described, the combination of positioning means against which a shoe is held by the hands of the operator, and handles on the positioning means extending beyond each end of the positioned shoe and arranged to be grasped by digits of the operator's hands while other digits hold the shoe against the positioning means.

69. In a machine of the class described, the combination of means for positioning the heel of a shoe longitudinally and laterally, means for engaging the tread face of the forepart of the shoe, and a handle extending be-

yond the forepart in position to be grasped by the operator's fingers while the operator holds the shoe with his thumb against the forepart engaging means.

70. In a machine of the class described, the combination of means for positioning the tread face of a shoe, handles on the positioning means extending longitudinally beyond the shoe and arranged to be grasped by the operator's fingers while his thumbs engage the shoe, a cutter for operating on the heel breast, and means for relatively moving the positioning means and the cutter to cause the cutter to operate on the heel.

71. In a machine of the class described, the combination of positioning means against which a shoe is held by the hands of the operator, extensions on the positioning means provided with finger holes located to receive the fingers of the operator's hands while his thumbs press opposite ends of the shoe against the positioning means, a rotary cutter, and means for relatively moving the positioning means and the cutter to cause the cutter to operate on the shoe heel.

72. In a machine of the class described, the combination of means for engaging the forepart of a shoe, means for locating the heel of the shoe, a handle on the locating means extending beyond the rear part of the shoe in position to be grasped by the fingers of the operator's hand while his thumb presses the rear part of the shoe against the heel locating means, and a rotary cutter, said locating means being movable by the handle to cause the heel to engage the cutter.

73. In a machine of the class described, the combination of positioning means against which a shoe is held by the hands of the operator, handles on the positioning means extending beyond each end of the positioned shoe and arranged to be grasped by digits of the operator's hands while other digits hold the shoe against the positioning means, and a rotary cutter, said positioning means being movable about an axis perpendicular to the cutter axis to cause the heel to engage the cutter.

74. In a machine of the class described, the combination of a rotary cutter, means for positioning the heel of a shoe longitudinally and laterally with respect to the cutter out of contact therewith, means for engaging the tread face of the forepart of the shoe, and a handle extending beyond the forepart in position to be grasped by the operator's fingers while he holds the shoe with his thumb against the forepart engaging means, the shoe being movable by the handle to cause the heel to engage the cutter.

75. In a machine of the class described, a rotary cutter on a stationary axis, and a shoe support movable to bring the shoe into the field of action of the cutter to cause the heel to be breasted, said support being also

movable about an axis adjacent to the heel to cause the cutter to follow the curve of the shank.

76. In a machine of the class described, 5 the combination of a rotary cutter, a shoe support arranged to receive a shoe with the plane of its bottom substantially perpendicular to the axis of the cutter, a slide for the support, a treadle connected to the slide 10 for moving the support toward the cutter in one direction, and means operating as an incident to movement of the slide for moving the support longitudinally of said cutter axis.

77. In a machine of the class described, a cutter on a horizontal axis, a shoe support mounted for movement perpendicular to the cutter axis and in a plane parallel to said axis, means for moving the support perpendicular to said axis, and means operating 20 as an incident to said movement to move the support longitudinally of the axis away from the cutter, the shoe support and cutter being then relatively movable in a plane 25 parallel to the cutter axis to effect action of the cutter to scallop the breast of the shoe heel.

78. In a machine of the class described, a cutter on a horizontal axis, a shoe support 30 arranged to turn on an axis perpendicular to the cutter axis and movable longitudinally of said cutter axis, and means for effecting relative movement of the support and cutter in a plane parallel to the cutter axis to effect operation of the cutter on the 35 heel breast of the shoe.

79. In a machine of the class described, 40 the combination of a rotary cutter, shoe positioning means arranged for rectilinear movement in two directions, one parallel to

the cutter axis and the other perpendicular thereto, means for moving the positioning means toward the cutter in the direction perpendicular to its axis, and means acting as an incident to said movement for moving 45 the positioning means in the direction parallel to the cutter axis.

80. In a machine of the class described, the combination of a rotary cutter, shoe positioning means arranged for rectilinear 50 movement in two directions at right angles to each other and for rotation about an axis perpendicular to the axis of the cutter, means for moving the positioning means toward the cutter in one of said directions 55 perpendicular to the cutter axis, and means acting as an incident to said movement to move the positioning means away from the cutter in the other direction longitudinally of the cutter axis, the positioning means being turnable on its axis when so located to effect action of the cutter on the shoe.

81. In a machine of the class described, the combination of a rotary cutter on an axis having a fixed location, a shoe positioning means movable perpendicularly to said axis and parallel to the direction of said axis and rotatable on an axis perpendicular to the cutter axis, means for moving the positioning means perpendicularly to the cutter axis, and means operating simultaneously to move the shoe positioning means parallel to the direction of the cutter axis, said positioning means being then 70 movable on its axis to cause the shoe to be 75 presented to the cutter to effect a scalloping operation on the breast of the heel.

In testimony whereof I have signed my name to this specification.

ELMER B. GRUSH.
